FABRIC CUTTER

Nathan Ross, Los Angeles, Calif.

Application January 23, 1934, Serial No. 707,937

8 Claims. (Cl. 164—76)

This invention relates to a fabric cutter of the rotary type.

An object of the invention is to provide a fabric cutter, adapted for use in conjunction with different kinds of fabric cutting machinery, which will more effectively prevent the lint produced by the cutting operation from obtaining access to the bearings of the machine or from becoming impacted between the relatively moving parts thereof. Carrying out this improved feature of the invention the rotary cutting element is constructed in such a manner that there is not only an improved circular joint between said member and the adjacent stationary part of the machine, but the shape of said member is such that the centrifugal force produced by the rotation thereof acts more effectively upon the lint to keep it from entering the bearings or becoming wedged between the relatively moving parts of the machine.

Another object of the invention is to provide a rotary cutter which is furnished with means to keep its inner side slightly spaced away from the adjacent stationary part of the machine so that wear and objectionable friction will be therefore reduced to a minimum.

Still another object of the invention is to simplify a structure of the character to which the invention pertains, to render its parts very simple and easy to manufacture, and to safeguard the cutting elements from breaking or getting out of order.

The present invention relates to an improvement upon a structure shown in my allowed application, Serial #646,456, filed December 9, 1932, now Patent No. 1,949,490, issued March 6, 1934, for patent on Fabric cutting device. The improvement hereinafter described and claimed pertains to stabilizing certain parts so as to more effectively prevent them getting out of order, as well as to the improved features above enumerated.

Other objects, advantages and features of the invention may hereinafter appear.

Referring to the accompanying drawing which illustrates what is at present deemed to be a preferred embodiment of the invention,

Fig. 1 is a face view of the inner face of the composite cutter member.

Fig. 2 is a vertical mid-section of the device, parts being broken away to contract the view.

Fig. 3 is a sectional detail of a portion of the structures which make up the cloth cutting disc.

Fig. 4 is a sectional detail of a modified form of the structure shown in Fig. 3.

Fig. 5 is a sectional detail of another modified form of the structure shown in Fig. 2.

Referring in detail to the drawing, the operative parts of the device are mounted upon a base member 5 by means of a standard 6 having a foot portion 7. Said foot portion is seated in a recess provided therefor in the upper face of the base member 5 in order that the upper surface of said foot portion may be made flush with the upper surface of the base member 5. Said foot portion may be secured in place by any suitable means as by the cap screws 8.

The standard 6 together with its body portion 6b constitutes an upstanding support for the rotary cutter member 9 which is mounted within the outer twin bearing rings 10, 10a of a roller bearing, said bearing being completed by means of twin inner bearing rings 11, 11a and the ball bearing members 12 which are interposed between said inner and outer bearing rings. The body 6b of the standard is recessed as shown in Fig. 2 to aid in housing the bearing construction which has been described, said portion 6b having around said recess an annular shoulder 13 which supports the bearing ring 10 said bearing ring being fitted into said recess and held against rotation by a screw pin 14. Said annular shoulder 13 is broad enough to overlap the greater part of the bearing 10.

The cutter member 9 includes a tubular hub 15 said hub being shown integral with a bevel gear 16 which surrounds said hub at substantially the mid-length thereof. Describing the parts as viewed in Fig. 2 the inner bearing ring 11 is fitted upon the left hand end of the hub and is rendered nonrotatable with relation thereto by means of a spline 17, while the bearing ring 11a is fitted upon the right hand portion of said hub and is held in fixed relation thereto by means of the spline 18, the two last recited bearing rings being held snugly against opposite sides of the gear 16. The bearing is completed by means of the bearing rings 10, 10a and the ball bearing members 12, four of which are shown in Fig. 2. The bearing ring 10a is fitted within an attaching disc 28 said disc having a centrally outwardly directed flange 29 to which said bearing ring 10a is secured by means of the spline 30.

Describing further the rotatable cutting member 9, said member includes a cutting disc 19 having a central opening therethrough within which is fitted a mounting member 20. Said mounting member has an internal annular flange 21 which underlies the portion of the

disc 19 adjacent to said opening, said flange being bevelled at an acute angle with relation to the inner face of said disc. To the inner face of said disc may be secured an internal 5 annular guard plate 22 which has through it a central opening the edge of which is bevelled to fit within the annular groove which is located between the bevel of said flange and the inner 10 face of the cutting disc 19. The preferred method of securing the plate 22 to the cutting disc 19 is by means of a plurality of small screws 15 23 one of which is shown in Fig. 3. Said screws extend through countersunk openings 24 provided for them in the disc 19 and screw into a thickened bevelled peripheral portion 25 of the internal guard plate 22. The cutter member 9 is completed by means of the external annular cap plate 26 which is screwed on to a raised portion 20a with which the mounting member 20 is provided.

The peripheral portion 25 of the guard plate 22 will of course rotate with the other parts of the rotary member 9. In order to guard more effectively against lint or other foreign matter creeping in behind said guard plate, this plate is furnished with an inwardly directed ledge or shoulder 25a which overhangs the adjacent portion of the standard body 6b. In order to complete the space which receives this shoulder 25, the standard body is provided throughout its upper portion with a groove 27 the outer side of which is bevelled while its inner side extends at a right angle to the face of the support.

35 The attaching disc 28 is provided with a screw threaded periphery whereby it is screwed into an annular screw threaded shoulder provided therefor in the body portion of the standard. By this means the entire bearing structure is held in its operative position by the aid of the screw 31 which is screwed into the left end of the hub 15 as viewed in Fig. 2. The entire rotary cutter member is held in place by means of a second screw 32 which is screwed into the right hand end portion of said hub as viewed in Fig. 2.

The bevel gear 16 may be driven by a driver gear or pinion 33 carried by the motor shaft 34.

In the modification of the invention illustrated in Fig. 4 the cutter disc 19a is provided with an internal rib 25b which takes the place of the thickened peripheral portion 25 with which the guard plate 22 is provided as shown in Fig. 2, that is to say the cutter plate and guard plate are made in one piece as shown in Fig. 4. In the latter view the thickened portion of the cutter disc is provided with an annular bevel 40 which is adapted to fit against the bevelled portion of the flange 21 of the mounting member 20.

60 In Fig. 5 is shown another modification wherein the annular guard plate 22 of Fig. 2 is for the most part dispensed with, being replaced by an annular ring 22b which is triangular in cross-section, in this view an annular space 22s is permitted to remain between the ring 22b and the annular flange or lip 21, this space serving to collect any lint or dust which might otherwise enter the bearings.

70 With the exception of the splines provided to hold the bearings in place and the screw 14 which also aids in holding the bearings in place as shown in Fig. 2, the parts will be secured together by means of a press fit as stated in 75 the description of the structure patented in my

hereinbefore mentioned allowed application. The three splines shown in Fig. 2 together with the screw 14 supplement the press fit and safeguard against any play occurring as the result of long continued or hard usage of the device. 5

In Fig. 4 the rib 25b is furnished with an internally directed shoulder 25x. The shoulders 25b and 25x overhang the adjacent portion of the body of the standard as shown, to safeguard against lint or other foreign matter entering 10 the bearings.

I claim:

1. In a cloth cutter, an upstanding support having a recess in one side thereof; a bearing mounted upon said support and partly housed in said recess; a plate secured to said support to aid in housing said bearing, a rotatable cutter disc having a hub portion supported by said bearing, means to maintain said disc in its operative relation to said bearing, said disc having a circular central opening therethrough and said means including a mounting member which occupies said central opening of said cutter disc, said mounting member being provided with a peripheral flange the edge of which underlies the portion of said disc adjacent to said opening and is bevelled at an acute angle with relation to the inner face of said disc thereby forming in combination with said disc a groove, an annular internal guard plate underlying said cutter disc and having its inner edge bevelled to fit upon the bevel of said flange, and means to clamp said guard plate between said cutting disc and the bevelled portion of said mounting member. 35

2. In a cloth cutter, an upstanding support having a recess in one side thereof; a bearing mounted upon said support and partly housed in said recess; a plate having an annular outwardly projecting flange, said plate being secured to said support with said flange directed away from said recess to aid in housing said bearing, a rotatable member supported by said bearing, said rotatable member including a hub portion located within said bearing and a cutter disc projecting radially from said hub, a screw member screwing into the outer end of said hub to secure said cutter member thereto, said cutter disc having a central opening therethrough, a mounting member fitted within said opening and having an internal annular flange which underlies the portion of said disc adjacent to said opening, said flange being bevelled at an acute angle with relation to the inner face of said disc to cooperate therewith to form an annular groove, an internal guard plate having a circular central opening the edge portion of which is bevelled to fit within said groove, and an external securing cap having a screw threaded connection with said mounting member to clamp together all the parts which rotate with said cutter disc, and to grip the bevelled portion of said guard plate between said cutter disc and mounting member. 50

3. In a cloth cutting device, a roller bearing comprising twin outer rings, twin inner rings and ball bearing elements interposed between said inner rings and said outer rings, a support and a plate which cooperate to form a housing for said bearing, both the outer rings of said bearing being mounted in fixed relation to said support and plate, a cutter member having a hub portion which extends into and is secured to both the inner rings of the bearing structure, said hub portion having a screw threaded bore 70 75

therethrough, an internal screw screwing into one end of said bore and having a head which engages the outer side of one of the inner twin bearings, and an external screw screwing into the other end of said bore, said external screw having a head which aids in securing the cutter portion of the cutter member to its hub portion, the heads of said two screws operating to clamp together the parts between them in such a manner that they rotate as a unit.

4. In a cloth cutting device, a bearing including an inner and an outer ring, antifriction elements interposed between said rings, a support and a plate which cooperate to form a housing for said bearing, the outer ring element of the bearing being mounted in fixed relation to said support and plate, a cutter member having a hub portion which extends into and is secured to the inner ring element of the bearing structure, said hub portion having a screw threaded bore, an internal screw screwing into one end of said bore and having a head which engages the inner end of the bearing, and an external screw screwing into the other end of said bore, said external screw having a head which aids in securing said cutter member in place.

5. In combination, a cloth cutter disc adapted to be mounted upon a supporting bearing frame, a circular projecting member on said disc detachably secured thereto and spaced a predetermined distance from the cutting edge thereof adapted to fit around and over said frame to keep foreign matter out of said bearing.

6. In a cloth cutting device, a two-part or twin bearing each part of which consists of an inner ring and an outer ring with interposed antifriction elements; a housing wherein said bearing is supported, said housing having an annular shoulder which overlaps in an endwise manner

the greater portion of the outer ring of one of the parts of said two part bearing, a fastening means in said shoulder to secure such ring in fixed relation to the housing; a gear interposed between the two parts of said bearing and fixedly secured to both of its inner rings, said gear having a hub; a cutter disc; means to secure said cutter disc to said hub; and means to drive said gear.

7. In a device of the kind described, a rotatable cutter member comprising a hub portion, an antifriction bearing assembly surrounding said hub portion, a housing for said bearing assembly including an attaching plate at one side of said housing, said plate having through it an opening surrounded by a circular flange that fits around said bearing assembly and is internally unobstructed to provide for the insertion of said bearing assembly thereinto from that side of the housing.

8. In a cloth cutting device, a two-part or twin bearing each part of which consists of an inner ring and an outer ring with interposed antifriction elements; a housing wherein said bearing is supported, said housing having an annular shoulder which overlaps in an endwise manner the greater portion of the outer ring of one of the parts of said two part bearing, a fastening means in said shoulder to secure such ring in fixed relation to the housing; means to secure the outer ring of the other part of the bearing fixedly to said housing; a gear interposed between the two parts of said bearing and fixedly secured to both of its inner rings, said gear having a hub; a cutter disc; means to secure said cutter disc to said hub; and means to drive said gear.

NATHAN ROSS.
